UNITED STATES PATENT OFFICE

STANLEY T. SCHOFIELD, OF WILKINSBURG, PENNSYLVANIA, ASSIGNOR TO WESTINGHOUSE ELECTRIC & MANUFACTURING COMPANY, A CORPORATION OF PENNSYLVANIA

CONTACT MEMBER FOR OIL-IMMERSED CIRCUIT INTERRUPTERS

Application filed September 7, 1926. Serial No. 133,797.

My invention relates to electrical switching apparatus and more particularly to arcing contact members for oil-immersed circuit interrupters.

- 5 One object of my invention is to provide a contact member that shall have a rounded contour for producing a partial rolling movement during its engagement with a co-operating contact member.
- 10 Another object of my invention is to provide an arcing contact finger that shall produce a partial rolling movement across the face of a second contact member upon its engagement with, and withdrawal from, the
- 15 second contact member.

Another object of my invention is to provide a contact finger for circuit interrupters that shall partially roll to an advanced position during the withdrawal of a co-operating contact member and that shall snap into its circuit-closing position after the withdrawal of the co-operating contact member.

A further object of my invention is to provide an arcing contact member for circuit interrupters that shall be characterized by having a partial rolling movement and a partial sliding movement across the face of a co-operating contact member.

In contact fingers, as heretofore constructed, it has been customary to provide the contact member with a smooth face that slides into and from its final position against a co-operating contact member. During such sliding movement, arcs are drawn between the contact members that tend to pit their flat faces. When such contact member has become thickly pitted, the depressions and projections resulting therefrom interfere with the sliding movement of the co-operating contact member, with a corresponding lessening of the current-conducting capacity of the contact fingers and a marked increased in their rise in temperature.

By providing a contact member that engages its co-operating contact member with a partial rolling movement, the friction existing between the co-operating contact members is reduced by reason of the curve surface on the arcing finger that is able to roll over the inequalities in the surfaces of the

co-operating contact member, as distinguished from sliding thereover.

In the accompanying drawings,

Fig. 1 is a view, in elevation, of a portion of a circuit interrupter embodying my invention. 55

Fig. 2 is a view, partially in elevation and partially in section, of the arcing contact members that are employed in connection with the circuit interrupter mechanism shown in Fig. 1, at an intermediate position during their circuit closing movement, 60

Fig. 3 is an edge view of one of the contact members shown in Fig. 2, 65

Fig. 4 is an elevational view of the contact members shown in Fig. 2 in their circuit-closing position, and, 70

Fig. 5 is a view of the contact members at an intermediate position during their circuit-opening movement.

My invention comprises, in general, a circuit interrupter 1 having a pair of main stationary contact members 2 and a co-operating bridging member 3 that is actuated by a suitable pull rod 4, together with stationary arcing contact members or fingers 5 that are supported by the main contact members 2 for co-operation with movable contact members, such as switch blades 6, that are carried by the bridging member 3. 75

The elements 1 to 4, inclusive, may be of any preferred type, since the details of their construction form no part of the present invention, except insofar as they are necessary to complete the combinations with the arcing contact members 5 and 6, hereinafter more fully described. 80

A pair of arcing contact members 5 are secured, by means of a bolt 7, to each of the stationary contact members 2, which constitute base portions for the members 5. Each of the contact members or fingers 5 comprises a supporting strap 8, a tensioning spring 9, a current-conducting shunt 11 and a contact member 12 that is pivotally supported, as at 13, at the end of the supporting strap 8. The straps 8 are loosely mounted on the bolts 7, the upper ends of the straps extending through slots in the base portion of greater thickness than the strap, to permit a limited 95

amount of play therebetween, for a purpose to be hereinafter described.

Referring particularly to Fig. 2, each contact member 12 comprises an inverted cylindrical portion 14 that extends upwardly and encloses the lower ends of the strap 8 and spring 9. The spring 9 bears upon a projecting lug 15 mounted within the cylindrical portion 14 by means of rivets 16, so that the lug 15 is free to turn relatively to the spring 9. Exterioly of the cylinder 14 is mounted a contacting block 17, of peculiar configuration, for co-operation with the moving contact member 6. The upper, or inner, portions of the contacting blocks 17 are provided with flat seats 18 for the reception of the contact members 6. When the switch blade 6 is confined in a pair of the seats 18, they serve as a latch for delaying the separating movement of the blade 6 until a sufficient pressure is supplied thereto to spread the contact fingers 5 apart.

Below, or outwardly from, the seats 18 the contacting blocks 17 have rounded contours, as at 19, for securing a partial rolling movement of the contacting blocks 17 across the faces of the contact member 6 when the two contact members are moved into and out of engagement with each other.

When it is desired to close the arcing contact members, the contact member 6, which is usually in the form of a switch blade, is moved upwardly and into engagement with the outer curved edges 19 of the contacting blocks 17. Further upward movement of the contact member 6 causes the contact members 12 to turn about their pivotal supports 13 away from the contact member 6 and against the force of the springs 9. The deflection of the contact members 12 is entirely compensated for by the springs 9, and no relative movement takes place between the supporting straps 8 and the bolts 7. Accordingly, the contacting blocks 17 partially roll and partially slide across the faces of the contact members 6 until the latter pass the curved portions 19 and enter the seats 18, which is the final circuit closing position of the arcing contact members, as is shown in Fig. 4. When the contact member 6 is in its final circuit-closing position between a pair of contact fingers 5, the springs 9 bias the contact fingers 5 into firm engagement with the moving contact member 6.

Referring to Fig. 5, when the contact member 6 is withdrawn from engagement with the contact members 12, they tend to turn about their pivots 13 inwardly or towards the moving contact member 6. However, their amount of movement in this direction is limited by the engagement of the upper walls of the cylinder 14 with their supporting straps 8 and, accordingly, since the application of the turning force is above the center line of the pivots 13, the supporting straps

8 are both forced outwardly relative to the moving contact member 6. This pressure causes them to shift their positions relative to the bolts 7 from that shown in Figs. 2 and 4 to that shown in Fig. 5. Accordingly, the contacting blocks 17 partially roll and partially slide across the faces of the moving contact member 6 as it leaves the contact fingers 5.

When the contact member 6 has cleared the curved surfaces 19, the springs 9 tend to move the contacting blocks 17 into engagement with each other with a snap action, which movement causes the supporting straps 8 to again shift their positions relative to the bolts 7.

Accordingly, I have devised a contact finger for an oil-immersed circuit interrupter that is characterized by having partial rolling and a partial sliding movement across the faces of a co-operating contact member, while that co-operating member is moving into and out of engagement with a seat formed in the first-mentioned contact member.

It is to be understood that such changes in the proportioning, shaping and disposition of the component parts of my invention may be made as shall fall within the scope of the appended claims.

I claim as my invention:

1. A contact member including support means, a strap loosely supported thereon, a contact finger pivotally supported on said strap and having a contact-making face the outer contour of which is a curve comprising two sectors offset relative to each other.

2. A contact member including support means, a strap loosely supported thereon, a contact finger pivotally supported on said strap and having a contact-making face the contour of which is a discontinuous curve.

3. A contact member including support means, a strap loosely supported thereon, a contact finger pivotally supported on said strap and having a contact-making face comprising two surfaces offset relative to each other.

4. A contact member including support means, a strap loosely suspended thereon, a contact finger pivotally suspended on said strap and having a contact-making face the contour of which comprises two sectors offset relative to one another, one of said sectors being curved.

5. A contact member comprising support means, a pair of oppositely disposed contact elements, each including a strap loosely mounted on said support means and a contact finger pivotally supported on said strap, said contact finger having a contact-making face of such configuration as to provide a hump near the middle thereof and means to bias said contact fingers toward each other.

6. A contact member comprising support means, a pair of oppositely disposed contact

elements, each including a strap loosely supported on said support means and a contact finger pivotally supported on said strap, said contact fingers having contact-making faces 5 the middle portion of the surface of which is further from said pivotal supports than are portions of said surface immediately adjacent each side of said middle portion, and means to bias said contact fingers toward each other.

7. In a contact member, the combination including a supporting means, a pair of straps supported thereby, a pair of oppositely disposed contact-supporting members each 15 pivotally suspended on a strap, a contact jaw attached to each of the said contact-supporting members and means for biasing the said contact jaws toward each other.

8. A contact member for the conductors of 20 a circuit interrupter including a pair of supporting members suspended from a conductor, a pair of contact jaws each pivoted to one of said supporting members and means for biasing said jaws toward each other, said jaws being rotated against the bias of the said means about said pivot.

9. A contact member for the conductor of 25 a circuit interrupter including a pair of supporting members loosely suspended from said conductor, a contact jaw pivoted on each of said supporting members and a biasing means associated with each of said jaws and supporting members that are adapted to bias said jaws and supporting members toward each other.

35 10. A contact member for the conductor of a circuit interrupter including a pair of supporting members loosely suspended from said conductor, a contact jaw pivoted on each of 40 said supporting members and means for biasing said jaws and supporting members toward each other, the jaws being separated by their combined movement of rotation and revolution in opposition to the force of said biasing means.

45 11. A contact member for the conductor of a circuit interrupter including a pair of supporting members, loose engaging means for suspending said supporting members from 50 said conductors, pivot means on each of said supporting members, a contact jaw supported on each of said pivot means and means for biasing said contact jaws and supporting means toward each other, the jaws being separated by a movement of rotation about said 55 pivot means and a movement of revolution about said loose engaging means.

60 12. In an electric switch, the combination of a contact structure and a cooperating relatively movable contact, said contact structure comprising a base portion and two contact fingers carried thereby in opposed relation for engagement with the opposite sides of the 65 cooperating contact, each contact finger comprising a supporting strap loosely suspended

from said base portion, a contact member, means for connecting the contact member to the supporting strap, said means permitting limited angular movement of the contact member relative to the supporting strap, a 70 flexible conductor connecting the contact member and the base portion, and a spring biasing the contact member toward the cooperating contact.

75 13. In an electric switch, the combination of a contact structure and a cooperating relatively movable contact, said contact structure comprising a base portion having slots therein and two contact fingers carried thereby in opposed relation for engagement with the opposite sides of the cooperating contact, each contact finger comprising a supporting strap which is supported in one of said slots, the thickness of the supporting strap being less than the thickness of the slot to provide for 80 limited angular movement of the supporting strap, a contact member, means for connecting the contact member to the supporting strap, said means permitting limited angular movement of the contact member relative to 85 the supporting strap, a flexible conductor connecting the contact member and the base portion, and a leaf spring fixed to the base portion and biasing the contact member toward the cooperating contact.

90 In testimony whereof, I have hereunto subscribed my name this 31st day of August 1926.

STANLEY T. SCHOFIELD.
